UNITED STATES PATENT OFFICE.

AMMON K. JONES, OF NEOSHO, MISSOURI.

SUBSOILER ATTACHMENT TO PLOWS.

1,116,824.

Specification of Letters Patent. Patented Nov. 10, 1914.

Application filed April 1, 1914. Serial No. 828,820.

To all whom it may concern:

Be it known that I, AMMON K. JONES, citizen of the United States, residing at Neosho, in the county of Newton and State 5 of Missouri, have invented certain new and useful Improvements in Subsoiler Attachments to Plows, of which the following is a specification.

This invention relates to the sub-soiling 10 attachments for plows, and has for one of its objects to provide a simply constructed device which may be applied without material structural change to plows and similar implements of various forms.

Another object of the invention is to provide a simply constructed device of this 15 character which may be readily adjusted to control the depth to which the hoe portion of the device operates.

Another object of the invention is to provide a simply constructed device which may 20 be transferred from one form of plow or like implement to another.

Another object of the invention is to provide a simply constructed device in which 25 provision is made for releasing the hoe and preventing breakage of the parts in event of the hoe encountering abnormal obstructions.

With these and other objects in view the 30 invention consists in certain novel features of construction as hereinafter shown and described and then specifically pointed out in the claims; and in the drawings illustrative of the preferred embodiment of the invention. Figure 1 is a side elevation of a portion 35 of a conventional plow from the landside with the improvement applied. Fig. 2 is an enlarged plan view of the improved device with the beam in section on the line 40 2-2 of Fig. 1. Fig. 3 is a side elevation of the parts shown in Fig. 2. Fig. 4 is an enlarged perspective view of the combined gripping and holding members whereby the 45 device is supported from the beam of the plow.

Corresponding and like parts are referred to in the following description and indicated in all the views of the drawings by the same reference characters.

The improved device includes a beam 50 member including a stock or body 10 upturned at its forward end as represented at 11 and downturned at its rear end as represented at 12, the downturned portion 12 being adapted to receive the share of end-oiler blade 13.

The upturned portion 11 of the body 10 is designed to receive a holding device whereby the body is coupled to the beam of a plow, the latter being represented conventionally at 14. This holding device comprises coacting members 15-16 for engaging the opposite sides of the beam 14 of the plow at their forward ends. The members 15-16 are formed with their inner or contiguous faces conforming to the sides of the beam 14 and closely embracing the same. The member 15 is formed with inwardly directed portions 19-20, while the member 16 is provided with a socket 21 at its rear end. 60 The portion 19 extends toward but does not quite reach, the contiguous face of the member 16 which bears against the rear face of the beam 14 with the upwardly directed portion 11 of the body 10 engaging between the 65 inwardly directed offsets 19-20 as represented in Fig. 2, while the inwardly directed portion 20 engages in the socket 21 of the member 16. A clamp bolt 22 engages through the members 15-16 and thus enables them to be firmly clamped in position 70 against the plow beam. The members 15-16 may be adjusted upon the beam as required by simply loosening the nut of the bolt 22. The projecting portion 20 is provided with threaded apertures to receive set 75 screws 24 which are thus in position to bear against the rear face of the upwardly directed portion 11 of the body 10. By this simple arrangement an efficient and a convenient sub-soiler attachment is provided 80 which may be readily applied without material structural change to plow beams of various forms and clamped at any desired point upon the beam, while at the same time 85 the beam member of the attachment may be adjusted to control the action of the hoe portion 13, and when required, the vertical portion 11 of the beam 10 may be adjusted at its highest point and thus holding the 90 sub-soiler blade 13 above the ground and in 95 inoperative position.

Having thus described the invention, what is claimed as new is:

1. In a device of the class described, coacting members adapted to bear at one end against opposite sides of a plow beam; one of said coacting members having a socket 105 near one end and the other coacting member having a lateral projection for engaging in said socket and a recess to receive a subsoiler device, clamping devices operat- 110

ing through said coacting member, and holding devices operating through said recessed coacting member and adapted to engage the sub-soiler device.

5 2. In a device of the class described, coacting members adapted to bear at one end against opposite sides of a supporting device, one of said coacting members having a socket near one end and the other co-
10 acting member having a lateral projection for engaging in said socket and a recess to

receive a supported device, clamping devices operating through said coacting members, and holding devices operating through said recessed coacting member and adapted to 15 engage the supported device.

In testimony whereof I affix my signature in presence of two witnesses.

AMMON K. JONES. [L. S.]
